UNITED STATES PATENT OFFICE.

ROBERT HEAD, OF NEW YORK, N. Y., ASSIGNOR TO THE AEOLIAN COMPANY, A CORPORATION OF CONNECTICUT.

SOUND-BOX.

1,275,914.

Specification of Letters Patent. Patented Aug. 13, 1918.

Application filed August 9, 1917. Serial No. 185,317.

To all whom it may concern:

Be it known that I, ROBERT HEAD, a citizen of the United States, residing at New York, in the county of New York and State of New York, have invented new and useful Improvements in Sound-Boxes, of which the following is a specification.

This invention relates to sound-boxes for talking machines, and in particular to those of the so-called convertible or universal type, which may be used to play records of both the vertical- and the lateral-cut forms.

Under ordinary conditions, it is customary, due to the difference in the way in which the sound-waves are recorded in the grooves, either to shift the sound-box bodily from one position to another when changing from one type of record to a record of different type, or else to utilize a stylus bar having a shiftable stylus holder which may be moved from one position to another, according to the type of record to be played. In certain other forms of universal sound-boxes, two separate stylus holders are provided, one for use in playing each type of record, each holder being furnished with its own screw or other clamp to retain the stylus in place in the socket or bore of the holder. All of these constructions require appreciable manipulation before playing can be commenced, and some of them are comparatively expensive to manufacture.

The present invention has for its primary object to simplify the constructions above described, by avoiding all of the preliminary manipulation and reducing the number of necessary parts without, however, in any way impairing the effectiveness of the former constructions. According to the illustrated embodiment of the invention, a substantially L-shaped stylus bar is provided, the lower arm of which is both widened and thickened to permit the formation of a pair of spaced, parallel, vertical sockets therein, one for use when playing vertical-cut records and the other for lateral-cut records. This arm is then split vertically from end to end, so as to form two counterpart spring jaws, the plane of the split intersecting both sockets; and the arm is then fitted with a single, centrally-located clamping screw which acts to alternatively open or close the jaws, thereby releasing or

securing a stylus in either playing position or both styls at the same time. 55

In the embodiment of the invention illustrated in the accompanying drawing,

Figure 1 is a face view of a sound-box equipped with the improved stylus bar.

Figs. 2 and 3 are enlarged, fragmental 60 detail views of the clamp portion of the bar, Fig. 2 being a face view, and Fig. 3 an edge view.

Fig. 4 is a bottom plan view.

Fig. 5 is an enlarged view of the clamp- 65 ing screw.

Referring more particularly to said drawing, 1 designates the body of the sound-box, 2 the diaphragm thereof, 3 the stylus bar and 4 the spaced supporting parts or lugs 70 for the bearing-screws 5, between which latter the stylus bar is mounted to oscillate. All of the above parts function in the usual manner, and, with the exception of the stylus bar, are, or may be, of the usual or 75 any desired construction.

The stylus bar, as shown, is of one-piece construction. Its upper arm 3' is fastened at the free end thereof to the diaphragm in the usual way, while the lower arm 3" functions as the stylus holder. In the illustrated embodiment of the invention, which, for all practical purposes, may be regarded as preferred, the aforesaid lower arm projects laterally outward from the diaphragm, and is 80 thickened both vertically and horizontally to an extent sufficient to enable the formation therein of a pair of vertical sockets 6 and 6', which are arranged in spaced, parallel relation. The inner socket 6 is designed to receive the stylus when a lateral-cut or zig-zag record is to be played, and for that reason is disposed substantially in axial alignment with the upper arm 3' of the stylus bar, the outer socket 6' receiving 85 the stylus when a vertical-cut or hill-and-dale record is to be played.

The portion of the holder arm 3" between the sockets 6 and 6' is cut away both above and below the center of said arm, 100 thus leaving only a narrow horizontal neck 7, which connects the two vertical portions 8 and 8' wherein said sockets are immediately formed. The inner of these two vertical portions is extended upward beyond 105 the top of the outer portion 8', and is

2

formed with a pair of trunnions 9, which are disposed between the supporting lugs 4 and are engaged by the bearing-screws 5, the trunnions thus determining the axis of vibration of the bar. The effect of the above is to virtually provide two small holders which are distinct and separate from each other, though integrally connected by the neck 7, the arrangement of the inner holder 8 directly beneath the pivots or trunnions 9 and in line with the upper portion of the bar enabling the lateral vibrations set up by the recording of the sound-waves in the side walls of the grooves to be accurately and positively transmitted through the stylus bar to the diaphragm in the usual way when a lateral-cut record is being played. Similarly, the arrangement of the outer holder to one side of the axis of vibration of the bar, enables said holder to rise and fall in accordance with the elevations and depressions in the bottom of the groove, when a hill-and-dale record is being played.

In order to retain a stylus in either socket, according as one type of record or the other is to be played, the holder arm 3² is split vertically at 10 from end to end thereof, the kerf or slit passing through both sockets and through the connecting neck 7; also, it opens through the side and bottom edges of the two holders and the top edge of the outer holder 8', but terminates short of the trunnions 9 provided on the upper end of the inner holder 8, as indicated by the dotted line in Fig. 2. As a result of the formation of this slit, two oppositely-disposed, counterpart jaws are produced, which, by their movements toward and from each other, control both sockets simultaneously, and will grip or release the stylus with the same facility irrespective of the socket in which it may happen to be arranged. The movements of the jaws necessary to effect these actions are preferably obtained by a single screw 11, the shank 12 of which passes through registering openings 13 and 13' formed through the neck portions of the two jaws. Only one of these openings, namely the one formed in the rear jaw, is threaded, and, of course, only the outer or terminal portion of the screw shank has threads thereon, the front opening 13 and the inner portion of the screw shank being unthreaded. The screw is provided, however, with an intermediate enlargement or collar 14, which contacts with the front jaw, so that when said screw is turned in one direction, its collar will press said jaw toward the rear jaw, while rotation of the screw in the opposite direction will remove the pressure of said collar from the aforesaid front

jaw and thus enable it, in turn, to move away from the rear jaw, thereby releasing the needle.

I claim as my invention:

1. In a universal sound-box, a stylus bar having a laterally-projecting lower arm provided with two separate stylus sockets, and a single clamp for similarly controlling both sockets in unison. 65
2. In a universal sound-box, a stylus bar having a laterally-projecting playing arm formed with two stylus sockets disposed in spaced, parallel relation, and a single clamp for similarly controlling both sockets in unison. 75
3. In a universal sound-box, an L-shaped stylus bar having its playing arm enlarged and thickened and formed with two separate stylus sockets, and a single clamp for controlling both sockets simultaneously and in the same manner. 80
4. In a universal sound-box, a stylus bar having a pair of separate stylus sockets, and a single clamping jaw for alternatively opening or closing both sockets simultaneously. 85
5. In a sound-box, a stylus bar provided at one end with a pair of co-acting spring jaws, said jaws having a pair of separate stylus sockets formed between them, and means for controlling the opening and closing of said jaws. 90
6. In a sound-box, a stylus bar provided at one end with a pair of co-acting spring jaws, said jaws having a pair of separate stylus sockets formed between them, and a single clamping screw for controlling the opening and closing of said jaws. 95
7. In a sound-box, a stylus bar having at one end an enlarged and thickened portion which is split to produce a pair of co-acting spring jaws, said jaws having a pair of stylus sockets formed between them, and clamping means carried by said portion for controlling the opening and closing of said jaws. 100
8. In a sound-box, a stylus bar provided at one end with a pair of separate stylus holders, and with a neck connecting them, each holder comprising a pair of spring jaws, and a controlling device common to both pairs of jaws mounted on said neck. 110
9. In a universal sound-box, a stylus bar provided at one end with a pair of spaced, parallel stylus holders, and with a neck connecting them, and a single clamping screw mounted in said neck for alternatively opening or closing both holders simultaneously. 115
10. In testimony whereof I have hereunto set my hand.

ROBERT HEAD.
